COMBINED AGITATOR AND HOOD FOR WASHING MACHINE

Gunnard A. Oberg, Lakewood, N. Y.

Application July 24, 1957, Serial No. 47,072

Term of patent 14 years

(Cl. D49—1)

FIG. 1

FIG. 2

Fig. 1 is a side elevational view of a combined agitator and hood for washing machine, showing my new design; and

Fig. 2 is a top plan view thereof.

I claim:

The ornamental design for a combined agitator and hood for washing machine, substantially as shown.
